UNITED STATES PATENT OFFICE.

JOHN BAKER, OF HOOPESTON, ILLINOIS.

PROCESS-KETTLE FOR CANNED FRUITS, VEGETABLES, &c.

SPECIFICATION forming part of Letters Patent No. 759,411, dated May 10, 1904.

Application filed October 25, 1902. Serial No. 128,695. (No model.)

To all whom it may concern:

Be it known that I, JOHN BAKER, a citizen of the United States, and a resident of Hoopes-ton, in the county of Vermilion, State of Illinois, have invented certain new and useful Improvements in Process - Kettles for Canned Fruits, Vegetables, &c., of which the following is a full, clear, and exact description.

This invention has for its object to provide an improved construction of process-kettle of the type used in the cooking of canned fruits, vegetables, or the like; and the invention consists in the features of improvement herein-after described, illustrated in the accompany-ing drawings, and more particularly pointed out in the claims at the end of this specification.

In factories in which the canning of fruits, vegetables, and the like is conducted upon a large scale it is desirable that the process-kettles shall be arranged in a horizontal line, and in order that the trays or baskets of cans may be conveniently lifted into and withdrawn from the kettles it is customary to provide an over-head traveling hoisting apparatus. The lids or covers of the process-kettles must be provided with means whereby they may be tightly clamped to the tops of the kettles during the cooking of their contents, and it is also desir-able that means shall be provided whereby the lids or covers of the kettle may be conveniently swung away to uncover the kettle-tops to permit the cans to be introduced into and removed therefrom. In practice it is found highly objectionable to provide the lids or covers of the kettles with clamping mech-anism or supporting devices that extend to any considerable distance above the tops of the kettles, as this is found to seriously interfere with the back-and-forth movement of the hoisting mechanism across the tops of the kettles.

My present invention is designed to provide a process-kettle the lid or cover of which is provided with supporting and closing devices that do not project inconveniently above the top of the kettle and do not interfere with the

free movement of the hoisting mechanism over the tops of the kettles and in close proximity thereto whether the lids or covers be in open or closed position.

Figure 1 is a view in side elevation of a process-kettle embodying my invention. Fig. 2 is a view in vertical section on line 2 2 of Fig. 3. Fig. 3 is a plan view of the kettle with the cover or lid removed. Figs. 4 and 5 are enlarged detail views showing the mechanism for supporting the lid or cover of the kettle.

A designates the body of the kettle, that is preferably formed of wrought metal and is provided with suitable pipes B and C for admitting and withdrawing the water wherein the cans will be immersed.

D designates a steam-pipe that enters the kettle A beneath its perforated bottom a. The body of the kettle A is shown as provided with an offset chamber E secured thereto, into which chamber enters the lower part of a thermometer e and to which chamber is also, preferably, connected a blow-off valve e'. The chamber E is also connected by a pipe E' with the bottom of the kettle A, so as to insure a circulation of the water through the kettle and through the offset chamber E.

The lid F of the kettle is preferably formed of a wrought-metal disk that is secured to a cast-metal ring F'. The ring F' is shown as provided with an annular groove f, in which is held a packing-strip f', adapted to bear against the upper raised edge of the cast-metal top ring A², that is secured to the top of the kettle-body A. The top ring A² of the kettle has cast therewith a number of lugs a², to which are pivotally secured, as at a³, the clamp-links a⁴. These links are adapted to swing between the projecting arms f² of the cover-ring F', and the threaded ends of the links a⁴ are provided with wing-nuts a⁵, adapted to securely clamp the lid or cover in position upon the top ring of the kettle. At the top of the kettle is bolted, as at w and w', a vertical stand-ard or bracket G, in which is held in manner free to move in vertical direction the vertical lid-pintle H. Preferably the bracket G is of

U-shaped outline and is provided with a cover G', that is securely bolted thereto when the lid-pintle H is in position for use. That part of the lid-pintle H within the bracket G is 5 preferably square, and one of its sides is formed with a toothed rack h, adapted to be engaged by a pinion k, carried by a shaft k', that is journaled in the lugs g', formed on the side G' of the bracket G. To the shaft k' is 10 attached a hand-lever K, the free end of which is curved, as shown in Fig. 3, and extends alongside of the kettle-body and is adapted to engage a notched plate L, that is bolted to the side of the kettle. Upon the opposite side 15 of the lid-pintle H and within the vertical bracket G are placed the roller-bearings M, these bearings being held in position against displacement by pins or studs m. There are two sets of roller-bearings shown in the drawings, one set being arranged adjacent the upper part and the other set adjacent the lower part of the lid-pintle H.

The upper end of the lid-pintle H is round and sets within a journal-socket F², preferably 25 cast integral with the ring F'. By preference the upper end of the lid-pintle H is formed with a recess to receive a ball-bearing f⁴, and a seat for this bearing is formed at the top of the pintle-socket F². Preferably, also, a hole 30 f⁵ is formed at the top of the pintle-socket F², through which oil will be delivered to the top of the pintle H.

From the foregoing construction it will be seen that when the lid or cover F is in the 35 closed position (shown in Figs. 1 and 2 of the drawings) it will be securely retained by the wing-nuts a⁵. If now it is desired to uncover the kettle, the operator after loosening and turning downward the several clamping-bolts 40 a⁴ will swing upward the hand-lever K, thereby lifting the lid-pintle H, through the medium of the pinion k and rack h, until the lid or cover F is lifted clear from the top of the kettle. The operator will then swing the lid 45 laterally until the top of the kettle is completely uncovered, so that the racks or trays containing the canned fruit, vegetables, or the like may be withdrawn therefrom. By means of the hand-lever K, the pinion k, rack h, and 50 lid-pintle H the lid or cover can be readily lifted by the operator, and this, too, notwithstanding its great weight. By providing the roller-bearings for the lid-pintle H the lifting of the lid or cover with the least possible friction 55 is accomplished, as the tendency of the pinion k when actuated by the hand-lever K is to force the lid-pintle H into bearing with the rollers M.

With my improved mechanism it will be 60 seen that whether the cover of the kettle be opened or closed there is no part projecting materially above the top of the cover, and hence the can-hoisting apparatus can be swung

freely across the top of the cover without interference. This, as I have said, is an important feature, particularly in large factories 65 where the process-kettles are arranged in rows with an overhead hoisting mechanism adapted to travel back and forth across the tops of the kettles.

It is manifest that the precise details of construction above set out may be varied within wide limits without departing from the spirit of this invention. I wish it understood also that while the invention is particularly applicable for process-kettles and is described in connection therewith it may be used in connection with other receptacles, and I do not wish the invention, therefore, to be understood as limited to process-kettles.

Having thus described my invention, what I claim as new, and desire to secure by Letters Patent, is—

1. A kettle having a lid arranged to swing at substantially right angles thereto and provided with a pintle-socket, a vertically-movable and non-revoluble lid-pintle, the upper end of which sets within said pintle-socket, a fixed bracket connected to the body of the kettle, in which bracket said lid-pintle is sustained in manner free to move in vertical direction, a shaft mounted in said fixed bracket and an operating-lever carried by said shaft and connected to said non-revoluble pintle to raise said pintle, said lever extending forwardly at one side of the kettle.

2. A kettle having a lid arranged to swing at substantially right angles thereto and provided with a pintle-socket, a vertically-movable and non-revoluble lid-pintle, the upper end of which sets within said pintle-socket, a bracket connected to the body of the kettle, in which bracket said lid-pintle is sustained in manner free to move in vertical direction, a lever connected to said non-revoluble pintle and whereby said pintle may be shifted vertically to raise said lid and antifriction-bearings held within said bracket and against which bearings said lid-pintle rests.

3. A kettle or receptacle having a lid arranged to swing at substantially right angles thereto and provided with a pintle-socket, a lid-pintle having its upper end journaled in said socket, a bracket connected to the kettle for sustaining said pintle and provided at one side with roller-bearings to engage said pintle, and rack-and-pinion mechanism at the opposite side of said pintle whereby said pintle may be shifted to move the lid from the mouth of the kettle.

4. A kettle having a lid arranged to swing at substantially right angles thereto and provided with a pintle-socket, a vertically-movable and non-revoluble lid-pintle, the upper end of which sets within said pintle-socket, a fixed bracket connected to the body of the

kettle, in which bracket said lid-pintle is sustained in manner free to move in vertical direction, a lever pivoted to said fixed bracket in manner permitting said lever to swing in 5 vertical direction only, a shaft to which said lever is connected, said shaft being pivoted in said fixed bracket, a pinion mounted upon said

shaft and a rack on said non-revolute pintle and engaging said pinion.
